WALKWAY

Emil P. Crepeau, Minneapolis, Minn., assignor to Butler Manufacturing Company, Kansas City, Mo., a corporation of Missouri

Filed Nov. 13, 1967, Ser. No. 9,387

Term of patent 14 years

(Cl. D13—1)

Fig. 1.

Fig. 2.

Fig. 3.

Fig. 4.

Fig. 5.

FIG. 1 is a top plan view of a walkway embodying my new design, the break lines indicating interrupted length;

FIG. 2 is a side elevational view of same, the other side being substantially identical;

FIG. 3 is an end elevational view of same, the other end being substantially identical;

FIG. 4 is an enlarged fragmentary perspective view of a portion thereof; and

FIG. 5 is a greatly enlarged fragmentary sectional view taken along the line 5-5 of FIG. 4 in the direction of the arrows.

I claim:

The ornamental design for a walkway, as shown and described.
